FRANK L. MARSTON, OF PORTLAND, MAINE.

FLUID-PRESSURE BRAKE SYSTEM.

1,269,478.

Specification of Letters Patent. Patented June 11, 1918.

Application filed July 31, 1916. Serial No. 112,276.

To all whom it may concern:

Be it known that I, FRANK L. MARSTON, a citizen of the United States, residing at Portland, in the county of Cumberland and State of Maine, have invented certain new and useful Improvements in Fluid-Pressure Brake Systems, of which the following is a specification.

My invention relates to improvements in fluid pressure braking systems in which automatic devices, known as triple valves are used.

The objects of my invention are, first: to eliminate the shock and jar to passengers on a moving train, second: to eliminate the danger of derailing one or more cars in a moving train upon a curve: third, to decrease the wear and tear on the rolling stock and the strain on the braking apparatus all of which are caused by the sudden, complete and automatic application of the brakes to full emergency position upon the accidental breaking or pulling apart of the train hose, as occurs in the systems at present in use.

I attain these objects by a combination of pistons and valves attached to and working with the triple valve of the present systems. Said combination is shown in the accompanying drawings and hereafter described as applied to the Westinghouse quick acting triple valve, as used in air brake systems. But I do not restrict my claims to a combination applicable to a quick acting triple valve, nor to the Westinghouse apparatus, nor to the exact construction as represented in the accompanying drawings or following description,—which is applicable to Westinghouse apparatus only, but have represented it as thus applied to more fully describe the working parts and the result of their action.

No change is made in the Westinghouse triple valve in any of the parts thereof, excepting in the graduating stem, the old plug which screws into the opening X at the end of the stem being taken out, and a new plug, embodying all the features of my combination, being screwed into the aforesaid opening.

This combination, shown as a whole, and in connection with the general form of the Westinghouse quick acting triple valve, in Figure 1, which shows all working parts in release position, consists essentially of two

castings 20 and 23, which constitute the shell 55 or main body and contain the working parts. These castings are held together by flange bolts and the joints are made air tight by gaskets clamped between the castings.

Fig. 1 is a vertical section of the combination of the Westinghouse triple valve as usually shown in the descriptions of the same, together with my improvements, showing their working parts.

Fig. 1^A is a horizontal section of the bottom part of the casting 23 with the contained parts taken on the line x—y in Fig. 1, and u—v in Fig. 2, showing the valve seat r' with its port openings. A bottom view of the slide valve 36 is also shown with its 70 recess s' and a portion of the rod 26.

Fig. 2 is a view of the inside of 23 with the flat ring 35 removed to show the passage e'.

Fig. 3 shows a vertical section of my improvements together with a small portion of the Westinghouse parts, being a part of Fig. 1, shown in the emergency position but on a larger scale.

Fig. 3^A is a horizontal section taken 80 through the center of the rod 21 showing a portion of the same passing through the sliding collar 37 and the ring k which is held in place by a pin passing through the rod and ring.

Fig. 3^B shows a horizontal section through the center of the piston 27, sliding ring 30, the lock nut 28, and a part of the rod 26, showing the pin passing through the rod and nut. The top of the slide valve is shown 90 with a part of the flanges removed to show the pin which holds the spring 25.

Fig. 4 is a vertical section of the lower part of Fig. 3 in automatic emergency position, and Fig. 4^A is a view of k. 37, 95 and a part of 21 in connection with the Westinghouse parts in the same relative position.

On account of the small scale of the drawing as shown in Fig. 1, and consequent difficulty of lettering the same, I hereby, in the following description, refer to the detailed views as well as the general view which is depicted in Fig. 1.

The large piston in the chamber d', having the same diameter as piston 5 in the present Westinghouse triple valve, is rigidly attached to the rod 21 which passes through

the stem of the threaded plug forming a part of 20, and a movable shoulder 37 engages one end of a spring 22.

A piston 27 in chamber e' is held rigidly 5 against a shoulder on the rod 26 by a nut 28. A spring 29 resting against one face of the piston 27 holds a movable washer 30 against a shoulder on the rod 26, which passes through the spring 29.

10 The rod 26 is loosely attached to a slide valve 36 moving in the chamber r' . All chambers containing pistons or valves are brass lined.

The chamber r' is connected with the pressure chamber H by a small pipe screwed into a threaded opening in chamber r' . The size of this pressure chamber should be governed by the size of the auxiliary reservoir connected with the chamber of the triple 20 valve proper, and should be so proportioned that the port a' would not exhaust the pressure too rapidly into the train line when the same is accidentally opened or broken. The object of this second auxiliary 25 reservoir is, first: to receive the compressed air from the train pipe and supply the same to the chamber d' to resist any movement to the right of the piston 24. Second: to supply a propelling force to the piston 27 with 30 its controlling valve 36 when the pressure in any manner is reduced in the chamber e' .

The tension of the spring 32 which rests in the plug 33 and against the shoulder 31 on rod 26 is equal to a pressure on the face 35 of the piston 27 of about 10 pounds to the square inch and can be graduated to correspond to the limit of service reduction desired by the plug 33 which is locked in the required position by a lock nut 34.

40 The tension of the spring 29 resting against the piston 27, and the sliding collar 30, is equal to the pressure of about 10 pounds to the square inch on the face of the piston 27, or about the difference between the reduction of service and the reduction of emergency.

In the release position of the device, shown in Fig. 1, the piston 5 is against the shoulders at the extreme left, the slide valve 50 3 is at the extreme left, the port opening z is closed by the bottom of the chamber, the recess n connects the brake cylinder port r with the exhaust port P allowing the brake springs to hold the brakes at release. The 55 piston 27 is held at the extreme right by the tension of the spring 32; the recess s' in the slide valve 36 is over the exhaust port h' . The pressure in the train line passes in at A, e. g., past the piston 5 by the groove i 60 to the chamber m and the auxiliary reservoir B, raising the pressure in this reservoir to that of the train line, also from the train line A, e, a' , a'' to the chamber d' , and a' to the chamber o' , by the groove n' to the 65 chamber r' and the pressure chamber H and

by port f' passage $e' e'$ to the chamber d' equalizing their pressures with the train line.

The service action used in ordinary stops is the same in the original Westinghouse parts as it is in the present arrangement. There is no action in the new parts—my combination. The spring 32 prevents any motion in the piston 27 by holding it to the extreme right with a force strong enough to 70 overcome the counter force caused by the ordinary service reduction of pressure in the chamber o' . The pressure in the chamber d' remaining nearly the same, would be slightly higher than that in m , which 75 slightly expands when piston 5 moves to the right. The projection j striking the rod 21 attached to the piston 24 prevents any further motion of the piston 5: the action of service and release continues as in the present arrangements.

The emergency action is caused by the engineer throwing his valve lever into emergency position, and is the same in the Westinghouse parts as in the present arrangements. In the new parts which are embodied in my invention, the following action takes place: the air in the train line is reduced between 10 and 20 pounds to the square inch by the said action of the engineer, causing the air to flow by the ports a' , e , etc., to the train line from the chamber o_2 until pressure in both are equal. Then the pressure in the chamber r' and the pressure chamber H being so much greater than that in o' , forces the piston 27 with the slide valve 36 to the left, overcoming the tension of the spring 32 until the collar 30 rests in the recess m' ; the tension of the spring 29 95 then coming into effect prevents any further movement of the piston 27 and the slide valve 36 which is now in such a position that the recess s' connects the exhaust port h' with the port f' allowing the air to escape from the chamber d' by way of passage e' 100 $e' f' s'$ to the exhaust port h' until the pressure in the chamber d' is the same as that of the atmosphere, when the piston 5 drives the rod 21 and the piston 24 to the extreme 105 right, overcoming the tension of spring 22 as it does in the present arrangement. The various parts will then be in emergency position as shown in Fig. 3.

The position of the various Westinghouse parts and their action is the same as in 110 the present arrangement. The action of release in the Westinghouse parts is the same as in the present arrangement. The action of release in the new parts is as follows:

The pressure being raised in the train 115 line through the engineer's valve, flows in by the passage $e' e' a' a'$ to the chamber o' raising the pressure to a point slightly higher than that in the chamber r' , allowing the spring 32 to force the piston 27 to the 120

extreme right, returning it with the slide valve to their former positions, and allowing the air in the chamber r' and pressure chamber H to flow by the port f' and passage $e' e'$ to the chamber d' , returning the piston 24 and the rod 21 to their former positions, when it again flows into the chamber r' by the groove n' raising the pressure in the pressure chamber H to that in the 10 train line.

The automatic emergency action is caused by the breaking or pulling apart of the train hose. The air in the train line is exhausted to atmospheric pressure almost instantly. 15 Pressure in o' exhausts by train line and passage $e' e' a' a'$ to atmosphere, allowing the pressure in r' which is nearly as high as formerly, to force piston 27 rapidly to the extreme left, overcoming the tension of both 20 springs 32 and 29 and causing the slide valve 36 to rapidly pass the emergency position allowing but a slight reduction of pressure in chamber d' by passage $e' e'$ and port f' to exhaust port h' while recess s' is passing over them, allowing piston 5 to force rod 21 and piston 24 to the right until the shoulder k on rod 21 strikes the collar 37 when the spring 22 resists further motion. The slide 25 valve t' now covers the exhaust port h' and the recess s' connects port f' with recess p' allowing the pressure in chamber r' to pass to chamber d' under the edge of 36 by recess $p' s'$ port f' and passage $e' e'$, again raising the pressure in d' to that in the second pressure 30 chamber H . Now the pressure in the auxiliary B has exhausted into the brake cylinder to a point slightly lower than that in the pressure chamber H , and the higher pressure in the chamber d' forces the piston 35 40 45 50 55 60 65 70 75 80 85 90 95 100 105 110 115 120 125 130

opening and closing of the port w in the slide valve 3 causes gradual application of the brakes in the automatic emergency stop, thus accomplishing the objects set forth in the beginning of my description.

What I claim as my invention and wish to secure by Letters Patent is the following combination of pistons and valves when applied to triple valves of fluid pressure braking systems:

1. Means for cushioning the operation of a brake valve comprising a casing having two chambers normally communicating with each other at points spaced from each other, one chamber having an exhaust port, a piston movably mounted in the other chamber, means for normally holding the piston at an initial position, means for applying uniform pressure at the opposite sides of the piston when at its initial position and at rest, the said communications between the chambers being so arranged that the pressure in both chambers is normally uniform, a valve movably mounted in the chamber having the exhaust port, a piston movably mounted in the last mentioned chamber between the communications connecting the chambers and connected with the valve, resilient means for holding the last mentioned piston at a normal position and the valve at a closed position over the port and means adapted to coöperate with the first mentioned piston after the beginning of its movement and before the end thereof to interrupt the passage of the pressure in that chamber in which it is located and thereby disturbing the balance of the pressure in the ported chamber whereby the piston therein moves the valve to an open position with relation to the port.

2. Means for cushioning the operation of a brake valve comprising a casing having two chambers normally communicating with each other at points spaced from each other, one chamber having an exhaust port, a piston movably mounted in the other chamber, means for normally holding the piston at an initial position, means for applying uniform pressure at the opposite sides of the piston when at its initial position and at rest, the said communications between the chambers being so arranged that the pressure in both chambers is normally uniform, a valve movably mounted in the chamber having the exhaust port, a piston movably mounted in the last mentioned chamber between the communications connecting the chambers with the valve, resilient means for holding the last mentioned piston at a normal position and valve at a closed position over the port, the last said chamber being provided with a groove which establishes communication with the opposite ends of the chamber and at the opposite sides of the last said valve when

the same is at one of its positions, and means adapted to coöperate with the first mentioned piston after the beginning of its movement and before the end thereof to 5 interrupt the passage of the pressure in that chamber in which it is located and thereby disturbing the balance of the pressure in the ported chamber whereby the piston therein is moved beyond the groove 10 and moves the valve to an open position with relation to the port.

3. In a device as described, a casing having a chamber and provided with an exhaust port, there being inlet ports communicating with the chamber at points spaced 15 from each other, a piston movably mounted in the chamber between the inlet ports, a rod fixed in the piston, a spring mounted on

the rod at a point between the ends thereof and adapted to encounter the casing when 20 the rod is moved and exert pressure upon the rod, a spring interposed between the rod and casing to hold the rod at a normal position therein, a valve carried by the rod and normally closing the exhaust port, the 25 parts being so arranged that the initial movement of the rod compresses the last mentioned spring and moves the valve to an open position over the exhaust port, and the final movement of the rod compresses 30 the first mentioned spring and moves the valve to a closed position over the exhaust port.

In testimony whereof I affix my signature.

FRANK L. MARSTON.
